CAN END INSPECTOR

Mark E. Moore, Maywood, Ill.

Application August 28, 1934, Serial No. 741,852

6 Claims. (Cl. 209—111)

This invention relates to improvements in means for detecting imperfect or undesirable articles in the process of their manufacture, and pertains particularly to a means for inspecting the ends of metallic cans, and this application constitutes a substitution for application Serial No. 713,218, filed February 27, 1934.

The primary object of the present invention is to provide a device whereby the ends of metallic cans may be automatically inspected after they have been formed and prior to their being applied to the can body, and removed from use if found imperfect in any manner as, for example, if found to be rusted, dirtied or without the usual gasket with which they are provided before being secured to the end of a can body.

In the manufacture of tin cans, the body of the can is first formed into a cylinder and after being flanged, is carried to a machine which applies and secures the ends thereto. These ends are cut from a sheet of metal and the disks thus formed have the edges turned or curled to hold a gasket in place and to also assist in locating the end on the can when the end goes into the seamer. After the end of the can has been formed and the gasket applied, it is conveyed on a belt or other suitable carrier to a stack from which it is taken and inspected before being transferred to a stack in the seamer from which it is fed for application to the can body.

At the present time, the inspection of the can ends is made by hand, therefore, the end cannot be kept entirely sanitary. The present invention contemplates the provision of a means of inspecting the can ends as they pass from the machine where they are curled and receive the gaskets to the seamer, on the endless conveyor. This inspection is carried out by means of a photoelectric cell and other mechanism operated thereby which is made active to remove an end from the conveyor if it is found to be rusted, greasy or dirty or to lack a gasket.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

55 In the drawings:—

Figure 1 is a view illustrating in top plan portions of the mechanism embodying the present invention, part of which mechanism is in section.

Figure 2 is a sectional view taken substantially upon the line 2—2 of Figure 1.

Figure 3 is a view of a portion of one unit of the device, a part of which is broken away to show the interior arrangement of the parts.

Figure 4 is a circuit diagram of an amplifier unit of the character which may be used in association with each of the can end inspecting units.

Figure 5 shows a modification of a portion of the circuit arrangement shown in Figure 4, which modified portion forms a part of the circuit layout for one can end inspecting unit.

Figure 6 is a diagrammatic illustration of two of the units showing the electrical connections between the parts thereof.

Figure 7 is a sectional view taken on the line 7—7 of Figure 1.

Referring now more particularly to the drawings, wherein like numerals of reference indicate corresponding parts throughout the several views, it will be seen upon referring to Figure 1 that there are illustrated three units which are indicated by the numerals 1, 2, and 3. These units are arranged in the relation illustrated above a belt 4 upon which the can lids are conveyed from the stamping machine where they are formed to the seamer machine, after having received the usual gasket or after having had the inner surfaces lacquered according to the practice followed. The units may be mounted in any suitable manner above the lid conveyor 4 as, for example, upon side rails 5 which extend in parallel relation along the side edges of the conveyor.

The unit 1 is designed for the inspection of can ends to determine if each one passing therebeneath has been equipped with the necessary liners. For this purpose, the unit is made up of two cylinders 7 and 8, which are mounted as illustrated in Figure 2, so that the open lower ends thereof are in convergent relation.

The cylinder 7 houses an incandescent lamp 9 and in the lower end is mounted a condensing lens 10 by means of which light rays issuing from the lamp 9 may be caused to converge on a small area adjacent the edge of each can end as it passes beneath the unit 1 on the belt 4. The cylinders, as shown in Figure 1, are mounted close to one side of the conveyor so that the spot of light passing through the lens 10 will strike the proper area of the end.

The cylinder 8 houses a light sensitive or photoelectric cell 11 and the arrangement of the cylinders 7 and 8 is such that the spot of light projecting downwardly upon the can end will be reflected therefrom, if the can end lacks the necessary liner or gasket, up into the cylinder 8 to strike this cell.

Mounted at the side of the conveyor adjacent each of the units 1, 2, and 3 is a solenoid coil 12 which has a longitudinally shiftable core 13. Adjacent each of the solenoids is mounted upon a vertical pivot 15, which may be carried by the adjacent rail 5, a kickout arm or bar 16 which has lateral extensions 17 at the pivoted end thereof through which the adjacent solenoid core 13 extends and with which the core has loose connection so that upon energization of the coil the core when it is drawn inwardly will pull upon the extensions 17 and swing the arm 16 across the top surface of the belt. A bracket 18 is mounted in spaced relation to the end of each solenoid from which the core 13 projects and a spring 19 is connected between each of these brackets and the adjacent kickout arm extension 17 so that the arm will normally be held at one side of and parallel with the conveyor.

In Figure 4 is shown a current amplifier unit which is indicated generally by the numeral 20 and which is illustrative of one form of circuit 30 which may be employed in association with the present invention. This circuit is controlled by the photoelectric cell 11 and when energized as a result of the necessary amount of light falling upon the cell 11, causes sufficient current to flow 35 through the relay unit 21 to swing an armature 22 thereof into contact with a terminal 23 so as to close a circuit 24 in which the solenoid coil 12 is located. The incandescent lamp 9 is also in this amplifier circuit, as illustrated in Figure 4, 40 and the current rectification and amplification is taken care of by a rectifier tube 25 of any suitable type such as a "25z5" tube and the amplifier tube 26 of a suitable type such as a "41" tube, the tubes being controlled by a rheostat 27 while 45 the light intensity necessary to activate the photoelectric cell 11 is controlled by the rheostat 28.

It is apparent from the foregoing that the sensitivity of the photoelectric cell 11 may be adjusted so that a can end passing beneath the light spot projected thereon by the lens 10 will be passed if it carries a liner which is insufficient to reflect the necessary amount of light to the cell 11 thus causing the energization of the same 50 and the building up of sufficient current in the amplifier circuit to actuate the relay 21. However, should the end lack a liner the bright metal of the end will reflect the necessary amount of light to energize the cell 11, the relay 21 will be 55 made active so that the arm 22 thereof will be drawn over into contact with the terminal 23 and the adjacent solenoid 12 will be energized and will cause the swinging of the arm 16 across the conveyor belt so that the imperfect end will be 60 knocked from the belt.

In order that the can ends approaching unit 1 may be in the proper position for inspection, the rails 5 carry light flexible arms 29, which serve to center the can lid.

Unit 2 employs the same amplifier circuit as unit 1, but this unit is intended to inspect those can ends which must have one face lacquered, and for this purpose, there is mounted over the conveyor belt a housing or cylinder 30 in the upper part of which a photoelectric cell 31 is

mounted. At one side of the housing or cylinder 30 is a small cylinder 32, which houses an incandescent lamp 33, this lamp and the cell 31 being analogous to the lamp and cell 9 and 11, respectively, as previously described and illustrated 5 in circuit in Figure 4. Leading from the incandescent lamp housing 32 through the wall of the cylinder 30 is a tube 34 which houses two converging lenses 35 which direct a spot of light from the lamp 33 onto a small dispersing mirror 36 which is mounted on an arm 37 in the cylinder 30 beneath the cell 31 and in such a manner as to spread the light over the conveyor belt 4 to include an area equal to the diameter of the lower end of the cylinder 30. This cylinder 30 15 is of substantially the same diameter as the can end so that the end passes beneath the cylinder and its entire surface will receive light from the mirror 36 and if it has not received its coat of lacquer, or areas are left uncovered by the lacquer, it will reflect the necessary amount of light 20 to activate the cell 31 so that the amplifier circuit will be energized and the defective end will be kicked out in the same manner as described in connection with the scanning of ends passing 25 under unit 1.

Unit 3 is intended to examine and remove from the conveyor belt 4 those can ends which may be dirty or rusted. This unit operates to remove from the belt those ends which fail to reflect a 30 sufficient amount of light instead of passing the same as the units 1 and 2 do. This unit, like unit 2, comprises a vertical cylinder 38 which has an open downwardly directed end overlying the belt and which houses a photoelectric cell 39 and a reflecting mirror 40 and which has a lens housing tube 41 extending through its wall and directed toward the mirror 40 for the projection thereonto of a condensed light beam issuing from an incandescent lamp 42 which is mounted in the vertical housing cylinder 43. The same form of 40 amplifying circuit is controlled by the cell 39 of unit 3 as is controlled by the cells of units 1 and 2, but a different form of relay is employed in which the solenoid circuit is broken when the relay is activated by the amplifier instead of being 45 closed as in the case of relay 21. In Figure 5 is shown a modified portion of the circuit of Figure 4 for use in connection with unit 3, wherein the relay is indicated by the numeral 44. The armature for the relay 44 is indicated by the numeral 50 45 and, as shown, when this is drawn over through the energization of the relay, it disconnects from a contact point 46 which is in the circuit 47. This circuit 47 contains the solenoid coil 12 which is associated with the unit 3 and in addition, it is controlled by two switch points 48 which are of thin flexible material and are located over the surface of the conveyor belt 4 beneath the edge of the photoelectric cell housing 38, as shown in Figure 1.

In the operation of the mechanism, when plain can ends are inspected, after the circuit controlling rheostats have been properly adjusted in connection with units 1 and 3, the can ends are 65 passed beneath these units upon the belt carrier 4. Each end first passes beneath the unit 1 where it is scanned adjacent its periphery by the light spot cast thereon from the lens 10. If the can end carries the required liner or gasket, insufficient light will be reflected therefrom to activate the cell 11 and the circuit controlled by this cell will remain inoperative so that the end will pass on toward the unit 3. The unit 2 may be cut out 70 of operation when the plain ends are examined, 75

- if desired, or if conditions require, the unit 1 may be cut out and the unit 2 allowed to scan the end in which case, the full end will be scanned, and if a gasket is present, the light reflected therefrom will be insufficient to activate the electric cell forming a part of this unit. It is, of course, understood that the circuit controlling rheostat of each unit is previously adjusted in accordance with the work which the unit is required to do.
- 5 5 In either case, if the unit 1 or unit 2 is used in the inspection of a plain end for the absence of a gasket or liner, the absence of the liner will reflect the amount of light necessary to cause the electric cell to increase the current flow through 10 the circuit in which it is located to the necessary degree to operate the relay 21, thus closing the circuit in which the adjacent solenoid 12 is located, so as to operate the kicked out element to cause the removal of the defective end.
- 15 20 The end, after having successfully passed the first unit by which it is inspected then passes beneath the housing 38 of unit 3 to be inspected for dirt or rust. The rheostat controlling the circuit for this unit is previously adjusted so that 25 the photoelectric cell 39 is sensitive to light reflected from a perfectly clean can end which is equipped with the proper liner. When such a can end moves along on the belt 4 into position beneath the cylinder 38, the photoelectric cell 30 becomes activated by the light reflected therefrom and causes sufficient current to pass through the relay 44 to swing the switch arm armature 45 so as to remove the same from the point 46, thus opening the circuit 47 at this point. The can end 35 will then contact and bring together the switch points 48, but the solenoid circuit 47 will remain open or inactive because of the separation of the armature 45 from the point 46. If, however, the can end which is scanned by the cell 39 contains 40 a dirty or rusty spot, the amount of light reflected therefrom will be insufficient to cause the energization of the photoelectric cell to the necessary degree to cause sufficient current to pass through the circuit for the operation of the relay 44 and, 45 therefore, the armature 45 and contact point 46 will remain in engagement one with the other so that when the end closes the switch points 48, the circuit 47 will be completely closed and the solenoid 12 will be energized to cause the kick out mechanism controlled thereby to operate for 50 the removal of the defective end.

In the use of the machine for inspecting lacquered ends, the course of a lacquered end without a gasket; a lacquered end with a gasket, but 55 showing white tin spots through as a result of the imperfect application of the lacquer thereto, and the course of a perfectly lacquered end having dirt or rust spots, will be traced. The units first have the controlling rheostats set so 60 that each will pass a good or properly lacquered end having a gasket.

First, a perfectly lacquered end without a gasket as it comes along on the belt 4, comes under the spot of light directed down in the curl where 65 the gasket should be, and there is an increase in light reflection which is transmitted to the photoelectric cell. This causes an increased flow of current through the circuit which the cell controls and the adjacent solenoid is then activated 70 and the end is expelled by the kick out lever.

Second, a lacquered end having a gasket but 75 having its surface imperfectly lacquered so that white metal spots show therethrough, will pass the first unit, but when arriving beneath the second unit, will be flooded with light, and due to the

increased reflection of light rays from the unlacquered spots, the cell of the second unit will be activated and the circuit closed for the ejection of the unit in the same manner as described in connection with the operation of unit 1.

5

Third, when a lacquered end with a gasket and perfectly applied coat of lacquer passes the first two units and arrives beneath the third unit with dirt upon the lacquered surface or with a rusted area lying beneath the lacquered surface, an entirely different action takes place in this unit 10 than in the two preceding ones. The feelers or switch 48, are an integral part of this third unit and as the end is scanned by the photoelectric cell as the end is carried into the spot of light which covers the whole unit, there is not an increase in the amount of light reflected to the cell, but a decrease from the amount a good cell would reflect to cause the relay 44 to be activated. This 15 decrease of light from what might be called the normal for this type of end fails to close the relay circuit and thus, when the end strikes the switch 48 and causes the points to be closed or brought together, the solenoid in circuit with the switch will be energized and the kick out lever 20 operated to remove the undesirable can end. Had the can end been perfectly clean, a sufficient amount of light would have been reflected, as a result of the adjustment of the controlling rheostat for this type of end, to cause current to flow 25 in sufficient quantity through the circuit to actuate the relay 44. This would have opened the circuit 47 at the point 46 so that when the switch 48 was closed by the can end, this circuit would 30 still remain inoperative and the end would pass on.

35 Every kind of end inspected requires a different adjustment of the amplifiers and the three units work together when they are properly adjusted, to pass a good end of whatever type or color. Then when an end comes under the units which is imperfect according to the standard to which the several amplifiers have been set, that end is naturally kicked out by that one unit which finds it imperfect.

40 While the foregoing is the preferred operation of the present invention, it is to be understood that the invention is not to be confined in use to the particular sequence of steps or operations set forth as other methods of using the units might 45 be employed. The unit 2, for example, might be used alone to sort ends by throwing out all good ones and allowing the bad or undesirable ones to be carried off, although this would be impractical for the reason that the solenoid would be caused 50 to operate almost constantly.

55 What is claimed is:—

1. Mechanism for inspecting normally shiny light reflecting bodies, comprising a conveyor for said bodies, a housing overlying the conveyor having an open lower side, a light sensitive element in the housing, means within the housing beneath said element for directing a light beam onto an article passing beneath the housing, an electric circuit including a relay and said element, said circuit and relay being made operative by the reception of a pre-determined amount of light by the element from a body, a second circuit, a switch in the second circuit having a pair of normally open switch points which are disposed to 60 be closed by the body carried on the conveyor for inspection as it arrives beneath said housing, said relay when energized opening a second switch in series with the first switch in the second circuit, and electrically operated means made operative 65

65

70

75

by the closing of the second circuit for removing an undesirable body from the conveyor.

2. A can end inspecting means, comprising a conveyor on which the ends are carried, a pair of inspection units each including an element movable across the conveyor to remove an end therefrom, an electric circuit, a light sensitive scanning element in the circuit and energizing the circuit upon receipt of a predetermined amount of light from the surface of a can end passing therebeneath, a relay for each unit and a second circuit controlled by the relay and including an electric element which when energized operates the movable end removing element, a switch in one of the second circuits, the said relays in the said one of the second circuits when operated opening said switch, and a second switch in series relation with the first mentioned switch in the last mentioned second circuit which is closed by the can end passing beneath the associated light sensitive element.

3. Mechanism for inspecting articles having light reflecting qualities, comprising a conveyor, a housing disposed over the conveyor and having a downwardly directed opening spaced from the conveyor to permit the passage of an end beneath the housing, said housing opening having an area of the same size as the surface of the article to be inspected, a light sensitive element in the housing, an electric circuit controlled by said element and including a relay, mechanism controlled by said relay which, when made operative, removes a receptacle end from beneath the housing, a light projector of a character to project light rays to a converging point, and a dispersing mirror within the housing beneath the element for receiving the converged rays of light from the projector and dispersing them over the area defined by the said housing opening.

4. Mechanism for inspecting articles having light reflecting qualities, comprising a conveyor, a housing disposed over the conveyor and having an opening directed downwardly toward the conveyor and spaced therefrom a sufficient distance to permit the passage of an article therebeneath an electric circuit including a relay, a light sensitive element in and controlling the circuit and disposed in said housing, a second circuit controlled by the relay, mechanism in the second circuit which, when energized, effects the removal of an article beneath the housing opening, a normally open switch in the second circuit disposed beneath the edge of said housing opening to be closed by contact of the side of an article therewith only when the article is fully in position beneath the opening, and means for diffusing light over the said article when it is brought to position before the receptacle opening.

5. A machine for inspecting light impervious and reflecting articles for conditions giving more than or less than a predetermined light value reflection, which comprises an article conveyor, a pair of housings fixed over the conveyor and each having an opening directed downwardly toward and spaced from the conveyor, a photo-electric cell in each housing, means in each housing for illuminating an article beneath the opening thereof, an amplifying circuit for and controlled by each cell, a relay in each circuit, a second circuit associated with each amplifying circuit, a switch in one of said second circuits which is closed by the relay in the associated amplifying circuit upon the activation to a required degree of the cell therein, electrically actuated means in the said one of the second circuits which when energized will remove an article from beneath the associate cell housing, a pair of switches in series relation in the other of the second circuits one of which is opened upon the energization of the associate relay, electrical means in the said other second circuit which when energized will remove an article from beneath the associate cell housing, and the other of said pair of switches being disposed adjacent the conveyor and adapted to be closed by an article only when the article is completely beneath the opening of the housing enclosing the cell with which the said other second circuit is associated.

6. Mechanism for inspecting normally shiny light reflecting bodies, comprising a conveyor for said bodies, a housing overlying the conveyor and having an open side spaced sufficiently from the conveyor to permit a body to pass beneath the opening, a light sensitive element in the housing, means for directing a light beam downwardly in the housing through said opening and onto an article passing therebeneath, an electric circuit including a relay and said light sensitive element, said circuit and relay being made operative by the reception of a predetermined amount of light by the element from a body, a second circuit, a normally open switch in the second circuit which is arranged between the housing and the conveyor to be electrically closed by a body carried on the conveyor for inspection only when the body is fully exposed to the light beam through said open side of the opening, a second switch in series relation in the second circuit with the first switch, said second switch being normally closed and opened only upon the energization of said relay, and electro-magnetically operated means in circuit with said switches which when energized effects the removal of a body from the conveyor.

MARK E. MOORE.
